UNITED STATES PATENT OFFICE.

WILLIAM S. HADAWAY, JR., OF NEW ROCHELLE, NEW YORK

ELECTRIC HEATING AND LIGHTING APPARATUS.

1,208,148.

Specification of Letters Patent. Patented Dec. 12, 1916.

Application filed September 26, 1913. Serial No. 791,934.

To all whom it may concern:
Be it known that I, WILLIAM S. HADAWAY, JR., a citizen of the United States, and a resident of New Rochelle, Westchester county, and state of New York, have invented certain new and useful Improvements in Electric Heating and Lighting Apparatus, of which the following is a specification, reference being had to the accompanying drawings, forming a part thereof.

My invention relates to electric heating and electric lighting apparatus and one of its objects is to provide an appliance or fixture having both lighting and heating elements which are adapted to coöperate in efficiently producing both heat and light.

It is of course well known that electric lights which depend upon electric energy for raising a solid member to an incandescent temperature, radiate heat as well as light. If a source of efficient electric light such as, for example, tungsten filament lamps should be utilized in a room or chamber for imparting heat thereto, it is obvious that in order to obtain the necessary heat, the light produced will be unbearable. On the other hand, if an efficient radiant heater which is adapted to deliver a relatively large quantity of heat, is utilized, there will of course be light emitted as well as heat but the amount of light will be insufficient and of undesirable color for the purpose of illuminating the area which is to be warmed by the heater.

According to my invention I utilize radiant electric heaters of such character that they produce large quantities of heat efficiently and at the same time produce a quantity of light which in itself is not entirely sufficient or of the proper color to constitute a desirable illuminant. However, I combine with the electric heating elements one or more lighting units which consume a relatively small amount of energy and which may in themselves produce light of a color which is highly desirable as an illuminant. By bringing the heating and lighting units into close proximity I secure the benefits of the quantity of light emitted from the heating elements which is blended

and combined with the light given off from the lighting elements.

It is obvious that by properly determining the number, and properly proportioning the capacities of the various elements, a highly desirable and efficient lighting and heating device may be secured. There is of course a certain amount of heat generated in the lighting elements and this heat is added to the heating elements.

Another object of my invention is to provide in a single artistic structure, a simple and effective radiant electric heater and one or more electric lamps, the structure having any suitable form as for example, a fixture corresponding to a wall bracket, or a portable device corresponding to an electrolier.

Another objects and advantages of my invention will be set forth hereinafter, and in order that my invention may be thoroughly understood, I will describe the same in the following specification, and then point out the novel features thereof in appended claims.

In the drawings: a fixture arranged and constructed in accordance with my invention is shown in front elevation in Figure 1, and in elevation in Fig. 2, the reflector being broken away and shown in section in Fig. 2. A modification of my invention is shown in Fig. 3.

The fixture illustrated in Figs. 1 and 2 comprises a wall bracket 10, a plurality of radiant heater units 20, a reflector 30, and a plurality of lighting units 14. The wall bracket 10 comprises a horizontal bar 11 to which are attached a plurality of upright sockets 12 and from which depend a plurality of lamp sockets 13. Lamps of any suitable type, such as incandescent lamps 14, may be mounted in the sockets 13. The reflector 30 comprises a hood 32 and is mounted on and may form a part of the wall bracket 10. I prefer to utilize radiant heater units of the general character set forth in my pending application Serial No. 791,931 filed at even date herewith, but the structural details of the heater units form no parts of my present invention and consequently will be only briefly referred to. Each of the units illustrated comprises a plug 21 which

is adapted to be inserted in one of the sockets 12, an insulated rod 22 extending upwardly from the plug and connected to one side of the supply circuit, and a resistance element 23 which is electrically interposed between the outer end of the rod and the plug and is mechanically supported about the insulated rod 22. Each of the units is preferably inclosed by a suitable casing 24 but this is to protect the unit and improve its appearance and is not intended to be a vacuum chamber or bulb. The units 20 extend into the hood 32 of the reflector. Each of the units is designed to operate at a very high temperature in order that a large proportion of its heat may be transferred from it by radiation and only a small proportion by convection.

It is a well known fact that heat may be transferred in three different ways, viz., by conduction, by convection, and by radiation. Conduction is the transfer of heat from one part of a body to another. Convection is the transfer of heat by the motion of heated matter and takes place only in fluids and gases. Radiation is the communication of heat from a hot body to a colder one across an intervening space and does not depend upon intervening air or any other tangible matter. The transfer of heat by radiation is supposed to be effected through the ether. Heat is transferred from electric heating devices, as ordinarily constructed, partly by radiation and in some cases by conduction, but ordinarily it is largely transferred by convection. In many ways this is the most unsatisfactory and uneconomical method of transferring heat and it has been my aim to produce a heater which is so designed and operated that a very large percentage of its heat is transferred, directly where it is wanted and used, by radiation.

The intensity of heat radiation from a given source varies as the temperature of the source, and inversely as the square of the distance from the source. I have consequently designed and arranged my heater units to operate at a very high temperature and I have designed the fixture to be placed in an elevated position in order that the distribution of radiated heat may be most effective.

The radiated heat rays are transmitted in all directions from the heated body but may be reflected by the use of a suitable surface, such as polished silver or brass. When the heating fixture is designed for mounting on a wall as the fixture shown in the drawings, I utilize a reflector such as the reflector 30, having a highly polished interior surface and arranged to prevent the radiated heat from heating the wall or the ceiling of the room in which the fixture is located and

reflecting all of the rays downwardly upon the floor of the room or objects located thereon. The units 20 may of course also give off light but this has no bearing upon my invention and the fact should be clearly borne in mind that radiation of heat does not in any way depend upon the radiation of light.

The structure of Fig. 3 is a portable device intended to replace an electrolier and in addition to providing an efficient light it embodies radiant heater units which are arranged to transfer the heat generated therein to outside bodies. The portable structure comprises a base or standard 50 having a central arm 51 which is crowned by a lighting unit 52, and a plurality of branch arms each of which supports a radiant heater unit 55. The portable structure may be utilized for various purposes as for example in the corner of a large room or near a window where a seat or couch is located and where good light and heat add materially to the comfort of the user.

The structures of my invention have the advantage of being utilized either solely as a source of lighting or heat or as a source of both heat and light.

While I have illustrated only two embodiments of my invention, I do not intend to be limited in this regard and variations and modifications will suggest themselves to those skilled in this art, consequently I intend that only such limitations be imposed as are indicated in appended claims.

What I claim is:

1. A combination heating and lighting apparatus comprising a radiant electric heater unit adapted to translate a relatively large quantity of electric energy into heat at a temperature which is sufficiently high to produce useful light, and a lighting unit adapted to translate a relatively small quantity of energy into light at a high temperature whereby the resultant light from the two units is available and constitutes the lighting effect of the apparatus.

2. A combination heating and lighting apparatus comprising a radiant electric heater unit adapted to operate at a temperature sufficient to produce a quantity of light, and a lighting unit adapted to produce a light of such quality as to effectively supplement and combine with the light produced by the heating elements whereby both units operate efficiently and co-operatively in proximity to each other.

3. A combination heating and lighting fixture comprising a support, a radiant electric heater unit mounted thereon and arranged to transmit a large percentage of heat generated therein by radiation, and to operate at a sufficiently high temperature to produce useful light, and a lighting unit

mounted on the same support, arranged to transform a large percentage of the electric energy consumed therein to light, and adapted to coöperate with the light produced by the heater and to determine the character of the effective light of the fixture.

4. A combination heating and lighting fixture having a support, a plurality of electrical heating devices carried on one side of said support, a plurality of electric

lighting devices carried on the other side of said support and a common reflector associated with said devices.

In witness whereof, I have hereunto set my hand this 24 day of September, in the year 1913.

WILLIAM S. HADAWAY, JR.
